(57) **CLAIM**

The ornamental design for a coffee filter holder, as shown and described.

DESCRIPTION

FIG. 1 is an environmental bottom plan view of a coffee filter holder showing my new design;

FIG. 2 is an environmental top perspective view thereof;

FIG. 3 is an environmental side view thereof;

FIG. 4 is a bottom plan view of the coffee filter holder alone;

FIG. 5 is an environmental top plan view of the coffee filter holder;

FIG. 6 is a side perspective view of the coffee filter holder alone;

FIG. 7 is a top plan view thereof;

FIG. 8 is a top perspective view thereof;

FIG. 9 is a bottom perspective view thereof; and,

FIG. 10 is a side view thereof.

The broken lines depict environmental subject matter only and form no part of the claimed design.
